UNITED STATES PATENT OFFICE.

EDWARD G. PARKHURST, OF HARTFORD, CONNECTICUT, ASSIGNOR TO HIMSELF AND THE PRATT & WHITNEY COMPANY, OF SAME PLACE.

CARTRIDGE PACKING-CASE.

SPECIFICATION forming part of Letters Patent No. 228,926, dated June 15, 1880.

Application filed May 6, 1880. (No model.)

To all whom it may concern:

Be it known that I, EDWARD G. PARKHURST, of Hartford, in the county of Hartford and State of Connecticut, have invented 5 certain new and useful Improvements in Cartridge-Cases; and I do hereby declare that the following is a full, clear, and exact description thereof, whereby a person skilled in the art can make and use the same, reference being had to the accompanying drawings, and to the letters of reference marked thereon.

Like letters in the figures indicate the same parts.

My improvement relates to cases which are used for packing and transporting cartridges 15 for machine-guns, and which are adapted to transfer the contained cartridges to the receiver of the gun directly from the packing-case.

20 The object of my invention is to provide a case which is simple and cheap of construction, and which will transfer the cartridges to the receiver of the gun in the most expeditious and simple manner possible, without having to draw off the case after the cartridges are inserted.

25 In the accompanying drawings, which illustrate my invention, Figure 1 shows a top view of my improved case with the top partly off, and before it has been pushed entirely on after the cartridges have been placed within it. Fig. 2 is a side view of the same. Fig. 3 is a cross-section through the case after it has been filled with the cartridges.

30 A and B are the two sides of the body of the case. They join together at the bottom C, where they are secured from being forced apart by a piece of paper, cloth, or other material glued to the bottom, and forming a hinge on which the parts can turn outwardly 35 when not held by the cover D. It is not necessary that this hinge should be sufficiently strong to hold after the cover is removed and the cartridges discharged from the case. The 40 cover, if made sufficiently stiff, would hold the two parts together without it.

D is the cover. It is intended to be made of tin or other sheet metal, and to be bent into the form shown in Fig. 3, with lips upon

the lower edges, which enter into grooves A' 50 in the sides of the body.

E is a central partition between the cartridges, which is attached to the cover by the tacks D' or otherwise, and moves with it when the cover slides on or off the body.

55 G is a separate and detached block, of the same thickness as the middle partition, E, which is placed between the two sides of the body when it is filled with cartridges, to hold them in place before the cover is put on.

60 H H are the cartridges placed on the case, as shown in the uncovered portion of Fig. 1. They rest against the middle block, G, and are held in the semicircular recesses in the sides of the body, as shown.

65 When the case is filled the cover, with its partition, is entered at one end, and slides on in the grooves A', the middle partition displacing the block G, pushing it out before it.

70 The block G is merely a temporary device for filling, and is not a part of the completed case when ready for transportation.

75 It is intended to cover the cases with paper after they are filled, which holds the cover on, and also will form a sufficiently strong connection at the bottom of the case between the two sides of the body. This paper will be ruptured in the act of putting the cartridges into the receiver of the gun. The cover rests upon a suitable seat upon the receiver, and the heads of the cartridges enter the grooves as they are usually constructed, 80 while as soon as the cover is entirely off the sides are detached and fly open or come apart, dropping away from the sides of the cartridges, 85 and requiring no withdrawal of the case to the rear to detach it.

90 The use of the removable block G, I consider the preferable method of filling the case with cartridges; but the block first inserted can be of the form of the partition E, and after the cartridges are inserted the cover D can be put on as described, but without a partition, and then the tacks D' inserted to hold the parts D and E together, so that they are 95 removed together, as before described.

What I claim as my invention is—

1. A cartridge-case constructed of the sep-

arable sides A and B, and the sliding cover D, provided with the partition E, substantially as described.

2. The combination of the sides A and B, the cover D, the partition E, and a hinge of paper or other material, C, attached to the bottom, substantially as described.

3. The combination of the removable block G with a cartridge-case having separable sides

provided with recesses for the cartridges, to serve as a temporary device to be used in filling said case with cartridges, as herein set forth.

EDWARD G. PARKHURST.
